FIG. 6.

UNITED STATES PATENT OFFICE.

ARTHUR J. BRIGGS, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,234,274.

Specification of Letters Patent. Patented July 24, 1917.

Application filed December 22, 1916. Serial No. 138,475.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines and more particularly to the combination with the line spacing wheel and platen of clutch mechanism by which the platen and line spacing wheel may be positively connected to rotate together, or the clutch may be released and the platen returned independently of the line spacing wheel.

My invention is directed more particularly to the type of platen clutch mechanism disclosed in the patents to Hubbard N. Josley, No. 945,956, dated January 12, 1910, and A. W. Smith, No. 860,834, dated July 23, 1907, and in which the line spacing wheel and platen may be positively connected at any point in the relative rotation between the two without displacing either of said members in effecting said connection.

One of the main objects of my invention, generally stated, is to provide a comparatively simple, strong and highly efficient platen clutch mechanism of the character specified.

A further object of my invention is to provide a platen clutch of the character specified, which may be readily embodied in existing machines, such, for example, as the No. 20 Yost machine, without modifying, or materially modifying, the structural features of such machines as they now exist.

To the above and other ends which will hereinafter appear my invention consists of the features of construction, arrangements of parts and combinations of devices set forth in the following description and particularly pointed out in the appended claims.

In the accompanying drawings, wherein like reference characters indicate corresponding parts in the different views,

Figure 1 is an enlarged detail longitudinal sectional view taken centrally through the platen.

Fig. 2 is an enlarged detail fragmentary sectional view of a member of the right-hand platen head and some of the asso-

ciated parts, the section being taken longitudinally and centrally of the platen.

Fig. 3 is an enlarged detail transverse sectional view taken on the line $x-x$ of Fig. 1 and looking in the direction of the arrows at said line.

Fig. 4 is an enlarged, detail fragmentary sectional view corresponding in part to Fig. 2 but showing the parts disposed at right-angles to the position in which they appear in Fig. 2.

Fig. 5 is an enlarged detail transverse sectional view taken on the line $y-y$ of Fig. 1 and looking in the direction of the arrows at said line, but showing the floating cam 35 in end view.

Fig. 6 is an enlarged detail fragmentary longitudinal sectional view corresponding to Fig. 1 but showing only the right-hand end portion of the platen and the clutch 75 locked in the released position.

Fig. 7 is an enlarged detail perspective view of one of the engaging pawls.

Fig. 8 is an enlarged detail fragmentary sectional view of the line spacing wheel.

Fig. 9 is an enlarged detail perspective view of a member of the right-hand platen head.

The platen, designated as a whole by the reference numeral 1, is of the usual construction and is mounted in the usual manner in the ordinary divided bearings 2 of the No. 20 Yost platen frame, some of the details of the bearing, however, being omitted. In this construction, a rubber sheath 3 surrounds a metal cylinder 4 secured to the left-hand platen head 5 by headed screws 6. The heads of these screws pass into openings in a ring 7 which surrounds the cylinder 4 at one end and abuts an end of the rubber sheath 3. The ring is held in position by the heads of the screws 6 and prevents a displacement of the sheath along the cylinder 4 in one direction. The right-hand platen head is secured to the platen in a like manner, and corresponding parts are designated by corresponding reference numerals. The hub of the left-hand platen head has a bearing member 8 received in the left-hand divided bearing 2, or in a suitable bushing contained therein. A circumferential collar or flange 9 on the hub takes against the bearing or its bushing. The part 8 is interiorly threaded to receive a screw 10 upon the shouldered spin-

105

95
100
105
110

dle of the left-hand finger wheel, the spindle and finger wheel being fixedly connected to the hub of the head 5 by set screws 11.

The right-hand platen head may be said 5 to comprise two members, one of which is the member shown in detail in Fig. 9 and is designated as a whole by the reference numeral 12. This member is fixedly secured to the platen by screws 6 which are 10 received in tapped openings 13 in opposite sides of the cylindrical body portion 14 of the member 12. A circular flange 15 formed on the member 12 extends beyond the associated end of the cylinder 4 and bears 15 against the same. The other member of the right-hand platen head is designated as a whole by the reference numeral 16, and is fixedly secured to the member 12 by headed screws 17 which take into tapped openings 20 18 in the member 12. The member or section 16 has a centrally arranged disk-like bearing portion 19 that is received within a flange 20 projecting from the end of the member 12, and bears against the end faces 25 21 of the member 12.

A line spacing wheel, designated as a whole by the reference numeral 22, is in the form of a ring and is provided at one end with line spacing teeth 23, and with 30 peripheral teeth 24 for coöperation with the usual platen detent. Inwardly extending wedge-shaped clutch teeth 25 project from the wheel beyond the body portion 26 thereof. The end or edge 27 of the line 35 spacing wheel bears against the outer face of the flange 15 on the member 12, whereas the body portion 26 of the wheel receives a bearing on the periphery 28 of the member 16. This brings the line of clutch teeth 25 40 outside of the flange 20 and within the space 29 in the member 16, so that the outer ends of the clutch teeth bear at 30 against the member 16, and the inner ends of the clutch teeth bear against the flange 15. In this 45 manner the line spacing wheel is mounted on the right-hand platen head for relative rotative movement, but the wheel is prevented from endwise displacement on the head except when the member 16 is detached.

50 The member or section 12 is formed with radial ways or channels 31, three such ways being shown in the present instance. In each of these ways is fitted a pawl or engaging member, designated as a whole by the reference numeral 32, and shown in detail in Fig. 7. When the member 16 is secured in place on the member 12 each way 31 is closed on four sides and is rectangular in cross section and open at its ends. The body 55 portion of each pawl is rectangular in cross section, conforming to the cross section of the way in which it is received. Each pawl is thus confined against lateral movement in its way, but is free to move therein radially 60 of the platen into and out of engagement

with the clutch teeth 25 on the line spacing wheel. The engaging end, or tooth, 33 of each pawl is wedge-shaped in cross section, conforming to the spaces between the clutch teeth 25. Each pawl is also formed within 70 the external dimensions thereof with a cam 34, for purposes which will hereinafter more clearly appear. A single conical controlling cam, or wedge-shaped member 35 co-acts directly with the inner ends of all three 75 pawls 32, to control the movements of the latter into and out of engagement with the clutch teeth 25. This cam is received in a central opening or channel 36 in the member 12, the diameter of the opening being 80 greater than the cam at the thickest part of the latter, so that the cam is capable of receiving a movement transversely of the platen, as well as longitudinally thereof. For this reason I refer herein to this member 85 35 as a floating cam to distinguish it from a cam which is movable in but one of said directions, and is guided and held against movement in the other direction. The opening 36 extends into an extension 37 90 formed on the member 12, and the coiled expansion spring 38 is received in said opening. One end of this spring bears against the bottom wall 39 of the opening and the other end of the spring bears against 95 the base of the conical cam. The force of this spring is exerted to move the cam outwardly, and to wedge or cam the pawls into engagement with the clutch teeth 25, and thus positively lock the line spacing wheel 100 to turn with the platen.

From a consideration more particularly of Fig. 5, it will be seen that in the present instance fifty clutch teeth 25 are provided on the line spacing wheel; that there are 105 three pawls 32 spaced at equal distances apart and which engage these teeth 25; and that the angular distance from the point of the tooth 33 on one pawl to either of the others, is not equal to the angular distance 110 occupied by any whole number of the teeth 25. It follows therefore, that no matter what the relative rotative adjustment between the platen and line spacing wheel may be, a positive connection may be effected between said parts without effecting a relative 115 rotative placement between them. It also follows that one of the three pawls will engage its tooth 25 on the opposite side from that of the tooth 25 engaged by another of 120 said pawls, so that relative rotative movement between the line spacing wheel and platen in either direction is prevented. Moreover, in a construction of this character all three pawls 32 will never engage the 125 teeth 25 to the same depth. All of this is well understood in the art and further explanation thereof herein is deemed unnecessary.

It will be seen that by reason of the fact 130

that all three pawls never engage the teeth 25 to the same depth, and that at different times each pawl may receive a greater or less depth of engagement, it is necessary for 5 the floating cam 35 to move transversely of the platen in different directions, as well as to move longitudinally of the platen. This is necessary in order that the cam 35 may maintain its coöperative relation with all 10 the pawls in their movements variable distances from the axis of the platen.

I have provided hand actuated means co-operative with the floating cam for releasing the clutch, in order that the platen may 15 rotate to any desired extent independently of the platen, and also have provided means for positively withdrawing the pawls from engagement with the clutch teeth, as well as means operable at will for locking the 20 parts indefinitely in the releasing position, all of which means will now be described.

The section 16 of the right-hand platen head has a hub 40 formed with a circumferential bearing groove 41 which receives 25 the two-part bearing 2 at the right-hand end of the platen frame, and thus forms a support for the right-hand end of the platen. This hub has a cylindrical opening 42 which extends longitudinally of and co-axially with 30 the platen, and in register with the opening 36 in which the floating cam 35 is received. The right-hand finger wheel 43 has a hollow spindle or stem 44, received at its inner end in the opening 42. A shoulder 45 on the 35 spindle abuts the outer end of the hub 40, and limits the inward movement of the spindle in the hub. Set screws 46 are received in tapped openings in the hub 40 and bear at their inner ends in depressions 47 40 (Fig. 4) in the spindle 44, thus fixedly connecting the finger wheel 43 to the platen.

The hollow spindle 44 is formed at its inner end portion, and on diametrically opposite sides thereof, with longitudinally extending slots 48. Projections 49 extend from the inner end of the spindle on opposite sides of the bore therein. Each projection has one face 50 which is in the same plane as a side wall of the associate slot 48.

50 A hand-actuated releasing member or spindle 51 extends co-axially with the platen, and is movable longitudinally thereof and rotatively in the bore of the hollow spindle 44. The outer end of the spindle 51 is provided with a finger wheel, finger piece or button 52 by which it may be manipulated. Oppositely disposed pins 53 project laterally from the spindle 51, and are received in the slots 48 when the parts are disposed as represented in Figs. 1, 2 and 3. When, however, inward pressure is exerted on the finger wheel or button 52 an inward longitudinal movement of the spindle 51 55 will displace said pins from the slots 48, moving them to the position represented in

dotted lines in Fig. 2. If it is desired to lock the releasing spindle 51 in the inward or releasing position to which it has been moved, it is merely necessary to give the finger wheel 52 a quarter turn; bringing the pins into the position shown in Fig. 6, and in dotted lines in Fig. 3. From a consideration of these figures, and Fig. 2, it will be understood that when the parts are moved to releasing position, shown in dotted lines 70 in Fig. 2, the projections 49 will permit the spindle 51 to be turned in but one direction, and then only to the extent of about a quarter turn, or until the pins 53 co-act with the projections 49 at the sides or edges 54 thereof. The projections 49 thus act as stops to limit the rotative movement of the spindle. At this time the pins rest on the end 55 of the hollow sleeve or spindle 44, and prevent an outward or return movement of the releasing member 51 until it is again turned to a position to bring the pins against the faces 50, and in register with the slots 48.

The inner end of the spindle 51 bears against a releasing member 56. This member is cylindrical in form and fits and is guided in the opening 42, and is limited in its outward movement by the projections 49. The inner end of this member 56 is formed with a conical internal cam face 57 which, as 90 will be understood from a consideration of Figs. 1 and 6, co-acts with the cams 34 on all of the pawls 32. The member 56—57 constitutes a cup-shaped cam which positively withdraws the pawls from engagement with the clutch teeth 25 when the spindle 51 is moved inwardly to the position shown in Fig. 6. The member 56 also receives the apex of the conical controlling cam 35, and the inward movement of the member 56 effects a corresponding movement of the member 35 against the force of the spring 38. This withdrawal of the cam 35 enables the pawls to be withdrawn inwardly, by the action of the cam 57 thereon. 100 It will be understood that in the movement of the cam 35 to the locking position, the member 56 in its coöperation therewith will not interfere with the lateral movement of the cam with the pawls to a position where 105 the cam is off-centered with reference to the axis of the platen. This off-centering of the cam 35 is shown in Fig. 5.

Additional means are provided for effecting a tie between the two platen heads 120 on the line of the axis of the platen, as is usual in the No. 20 Yost machine. Thus, a headed tie rod 58 is introduced through an opening 59 in the left-hand head, and this tie rod is threaded at its inner end, as at 125 60, for engagement in a tapped opening in the extension 37 of the right-hand platen head.

From the foregoing description it will be understood that the clutch may be tempo- 130

rarily released by merely pressing the button 52, and a relative adjustment between the platen and line spacing wheel may be effected while pressure is maintained on the button. After the proper adjustment has been effected the operator may release the pressure on the button 52, and the parts controlled thereby will be returned to the normal position by the single spring 38, and 10 an effective engagement of the clutch to connect the line spacing wheel and platen will be brought about. Should the operator desire to lock the clutch released and maintain it released indefinitely, it is merely necessary to turn the finger wheel or button 52 after it has been moved to the releasing position, in the manner hereinbefore described.

What I claim as new and desire to secure 20 by Letters Patent, is:—

1. In a typewriting machine, the combination of a platen; a line spacing wheel; and clutching means for positively connecting the line spacing wheel and platen to 25 turn together and for enabling the platen to turn independently of the line spacing wheel, said means comprising a series of teeth, co-acting engaging pawls, and a floating cam co-operative with all of said pawls 30 and operating thereon to force them into engagement with said teeth.

2. In a typewriting machine, the combination of a platen; a line spacing wheel; and clutching means for positively connecting the line spacing wheel and platen to 35 turn together and for enabling the platen to turn independently of the line spacing wheel, said means comprising a series of teeth, co-acting engaging pawls, a floating 40 cam co-operative with all of said pawls and controlling the movements thereof into and out of engagement with said teeth, a single spring which tends to force the pawls into engagement with said teeth through the operation of the cam on said pawls, and hand 45 controlled means for moving said cam against the force of said spring.

3. In a typewriting machine, the combination of a platen; a line spacing wheel; 50 and clutching means for positively connecting the line spacing wheel and platen to turn together and for enabling the platen to turn independently of the line spacing wheel, said means comprising a series of teeth, co-acting engaging pawls, a centrally 55 disposed floating member having a cam face co-operative with all of said pawls to force them into engagement with said teeth, and a second cam co-operative with all of said 60 pawls to withdraw them from engagement with said teeth and co-operative with said floating member to move it.

4. In a typewriting machine, the combination of a platen; a line spacing wheel; 65 and clutching means for positively connect-

ing the line spacing wheel and platen to turn together and for enabling the platen to turn independently of the line spacing wheel, said means comprising a series of teeth, co-acting engaging pawls, a floating 70 member having a cam face co-operative with all of said pawls to force them into engagement with said teeth, a second cam co-operative with all of said pawls to withdraw them from engagement with said teeth, a spring which tends to move the floating member in one direction and to cause the pawls to engage said teeth, and hand controlled means for forcing said floating member and the second cam in the opposite direction against the force of said spring and for positively disengaging the pawls from 75 said teeth.

5. In a typewriting machine, the combination of a platen; a line spacing wheel; and clutching means for positively connecting the line spacing wheel and platen to turn together and for enabling the platen to turn independently of the line spacing wheel, said means comprising inwardly projecting 80 clutch teeth carried by the line spacing wheel, pawls fixed to turn with the platen but movable radially of the platen into and out of engagement with said clutch teeth, and a centrally disposed floating wedge co-operative with all of said pawls and controlling the movements thereof into and out of engagement with said clutch teeth.

6. In a typewriting machine, the combination of a platen; a line spacing wheel; and clutching means for positively connecting the line spacing wheel and platen to turn together and for enabling the platen to turn independently of the line spacing wheel, said means comprising a series of teeth, co-acting engaging pawls, a centrally disposed floating cam co-operative with all of said pawls and controlling the movements thereof into and out of engagement with said teeth, a spring which tends to force the pawls into engagement through the operation of the cam on said pawls, and a hand actuated releasing spindle which extends coaxially with the platen and is effective to move said cam against the force of its spring 110 to the releasing position.

7. In a typewriting machine, the combination of a platen; a line spacing wheel; and clutching means for positively connecting the line spacing wheel and platen to turn together and for enabling the platen to turn independently of the line spacing wheel, said means comprising a series of teeth, co-acting engaging pawls, a floating cam co-operative with all of said pawls and controlling the 120 movements thereof into and out of engagement with said teeth, a spring which tends to force the pawls into engagement through the operation of the cam on said pawls, a hand actuated releasing spindle which ex- 125

- tends co-axially with the platen and is effective to move said cam against the force of its spring to the releasing position, and means operable at will independently of the releasing movement of said spindle for locking the latter in its releasing position.
8. In a typewriting machine, the combination of a platen; a platen head which carries a hub fixedly connected thereto and received in a bearing in the platen frame and by which the platen is supported at one end in the platen frame; a line spacing wheel carried by and adapted to turn on said platen head; inwardly projecting clutch teeth carried by said line spacing wheel; a plurality of pawls carried by said platen head and movable radially of the platen into and out of engagement with said clutch teeth; and means for controlling the movements of said pawls into and out of engagement, said means comprising a spindle arranged co-axially with the platen and movable through a central opening in said hub.
- 25 9. In a typewriting machine, the combination of a platen; a platen head which carries a hub fixedly connected thereto and received in a bearing in the platen frame and by which the platen is supported at one end in the platen frame; a line spacing wheel carried by and adapted to turn on said platen head; inwardly projecting clutch teeth carried by said line spacing wheel; a plurality of pawls carried by said platen head and movable radially of the platen into and out of engagement with said clutch teeth; and means for controlling the movements of said pawls into and out of engagement, said means comprising a spindle arranged co-axially with the platen and movable through a central opening in said hub, and a floating cam co-operative with all of said pawls and under control of said spindle.
- 45 10. In a typewriting machine, the combination of a platen; a platen head which carries a hub fixedly connected thereto and received in a bearing in the platen frame and by which the platen is supported at one end in the platen frame; a line spacing wheel carried by and adapted to turn on said platen head; inwardly projecting clutch teeth carried by said line spacing wheel; a plurality of pawls carried by said platen head and movable radially of the platen into and out of engagement with said clutch teeth; and means for controlling the movements of said pawls into and out of engagement, said means comprising a spindle arranged co-axially with the platen and movable through a central opening in said hub, a floating cam co-operative with all of said pawls, a spring which tends to move said cam in one direction and force the pawls into engagement with the clutch teeth, the cam being movable in the opposite direction under control of said spindle, and means for locking said spindle in its actuated or releasing position.
11. In a typewriting machine, the combination of a platen; a platen head which carries a hub fixedly connected thereto and received in a bearing in the platen frame and by which the platen is supported at one end in the platen frame; a line spacing wheel carried by and adapted to turn on said platen head; inwardly projecting clutch teeth carried by said line spacing wheel; a plurality of pawls carried by said platen head and movable radially of the platen into and out of engagement with said clutch teeth; and means for controlling the movements of said pawls into and out of engagement, said means comprising a spindle arranged co-axially with the platen and movable through a central opening in said hub, a floating cam co-operative with all of said pawls, a spring which tends to move said cam in one direction and force the pawls into engagement with the clutch teeth, and a second cam co-operative with all of said pawls to positively disengage them from the clutch teeth and which is moved to inoperative position by the action of said spring, said spindle being operative to shift both of said cams against the force of said spring.
12. In a typewriting machine, the combination of a platen, a two-part platen head, which receives a direct bearing in the platen frame, a line spacing wheel mounted to turn on said platen head and which is confined theron between the two parts of said head when they are fixedly connected, radial ways in one part of said head which are covered by the other part thereof when it is secured in place, sliding clutch pawls which move radially in said ways, clutch teeth on the line spacing wheel and with which the pawls engage, a single cam co-operative directly with all of said pawls, and a hand controlled releasing spindle which extends co-axially with the platen into said platen head and controls the movement of said cam.
13. In a typewriting machine, the combination of a platen; a line spacing wheel; and clutching means for positively connecting the line spacing wheel and platen to turn together and for enabling the platen to turn independently of the line spacing wheel, said means comprising a series of teeth, co-acting engaging pawls, a centrally disposed conical cam co-operative with all of said pawls to force them into engagement with said teeth, a cup-shaped cam co-operative with all of said pawls to positively move them out of engagement with said teeth and co-operative with the conical cam to move it to releasing position, and hand actuated releasing means co-operative with said cup-shaped cam.

14. In a typewriting machine, the combination of a platen, a line space wheel, a plurality of radially movable dogs, a universal cam operating on all of said dogs to keep them normally in engagement with said line space wheel, and a cup-shaped cam arranged to move the universal cam out of operative position and also to engage said dogs and withdraw them from engagement with said line-space wheel.

15. The combination of a platen, a line space wheel, a plurality of dogs radiating from the center of said platen, a sprung pressed universal cam arranged axially of said platen and operating on all said dogs

to keep them normally in engagement with said line space wheel, and an axially arranged manually movable cup-shaped cam arranged to move the universal cam out of operative position and also to engage said dogs and withdraw them from engagement with said line-space wheel.

Signed at Syracuse, in the county of Onondaga and State of New York, this 12th day of December, A. D. 1916.
